UNITED STATES PATENT OFFICE.

SAMUEL ROBERT, OF NEW YORK, N. Y.

DESIGN FOR A COMBINED MATCH HOLDER AND ASH TRAY.

Application filed January 12, 1924. Serial No. 8,299. Term of patent 14 years.

To all whom it may concern:

Be it known that I, SAMUEL ROBERT, a citizen of the United States, and a resident of the city, county, and State of New York, have invented a certain new, original, and ornamental Design for a Combined Match Holder and Ash Tray, of which the following is a specification, reference being had to the accompanying drawing, forming part thereof.

In the drawings,
Fig. 1 is a plan view;
Fig. 2 is a side elevation; and
Fig. 3 is a vertical section on line 3—3 of Figure 1.

I claim:

The ornamental design for a combined match holder and ash tray, as shown.

SAMUEL ROBERT.
